WIRE SUPPLY MECHANISM

Charles M. Fornwald, Jr., Linden, N. J., assignor
to Syncro Machine Company, Rahway, N. J.,
a corporation of New Jersey

Application December 8, 1942, Serial No. 468,247

14 Claims. (Cl. 242—78)

This invention is directed to improvements in mechanism employed for supplying wire and similar strands to wire processing machines, as for example wire drawing machines, functioning so as to prevent breakage of the wire or strand should the supply become locked or tangled.

The general combination of this invention comprises the association with any type of strand or wire processing machine, as for example a wire drawing machine, of mechanism for supplying the strand or wire from a coil and controlled by the wire for preventing its breakage in the event that the coils of the supply become locked or the wire kinked and tangled sufficiently to otherwise cause breakage thereof.

The many and detailed objects of this invention will be better understood following a detailed description of the embodiment thereof illustrated in the attached drawings rather than by a generalized description thereof at this time.

This invention resides substantially in the combination, construction, arrangement and relative location of parts, all as will be described in detail below.

In the accompanying drawings,

Figure 1 is a side elevational view of a wire drawing machine with which is associated the improved wire supply mechanism of this invention; Figure 2 is a top plan view thereof;

Figure 3 is an enlarged vertical, central, cross-sectional view with some parts in elevation of the improved mechanism of this invention;

Figure 4 is a right hand side elevational view thereof;

Figure 5 is a detailed broken view partly in cross-section showing the releasing device for the mechanism;

Figure 6 is a cross-sectional view showing this release mechanism in released position; and

Figure 7 is an enlarged detail, cross-sectional view of the wire drum cam locking device.

The description of the embodiment of the invention selected for the purpose of illustrating and describing the nature thereof will be made for the combination of a wire drawing machine with the wire supply mechanism of the invention. From the entire disclosure it will be apparent to those skilled in the art that the invention is not limited in its combination with wire drawing machines but may be employed with all types of strand processing machines where the strand is supplied thereto from a supply reservoir in the form of coils. Likewise, in some instances the invention may be of use in connection with the supply of strands from spools.

In Figures 1 and 2 a wire drawing machine 1 is illustrated in general outline only since it forms no part of this invention. The illustration includes a drive motor 2 for the wire drawing machine, a bull block 3, and a spooling mechanism 4. The wire supply mechanism of this invention is generally illustrated by the reference numeral 5. The wire W is placed on this mechanism in the form of a coil 6, which is supported thereon by any suitable form of holding and paying off support.

The mechanism itself comprises a framework of any suitable type, which as illustrated may comprise a standard 7, and a integral framework comprising angle bars 8 and 9 and plate 10. This framework may be built up in any suitable manner.

The wire in the form of a coil 6 is mounted upon a suitable turntable 11 from which the wire may be paid off as it revolves. The wire first passes through any suitable form of guide means such as the tube 12 forming part of the turntable, comprising part of the usual supply stand, and from which it passes to an adjustable tensioning or drag device 13 illustrated in Figure 4 as a pair of spring loaded friction plates of any suitable material. The wire W then passes through a guide 14 to an idler pulley 15 rotatably mounted on the free end of a lever 16. The wire then passes onto a rotatable carrier in the form of a drum 17, as illustrated, on which it lies in contiguous convolutions, the number of which suitable to the function of the machine, will be referred to later. The carrier comprises an auxiliary reservoir or storage member to which the wire travels on its way from the main supply coil 6 to the bull block 3. The wire then passes from the drum 17 to and around an idler pulley 18 rotatably mounted on the free end of an arm 19. The central plane of the idler pulley 18 lies substantially in a plane tangent to the cylindrical portion of the drum 17 on which the convolutions lie, as is clear from Figure 4. The wire then passes from the pulley 18 to the processing machine, as for example the wire drawing machine of the figures.

The arms 16 and 19 and the drum 17 are rotatably mounted on suitable bearings supported by tubular member 20 mounted in any suitable manner on the plate 10. The left hand end of the member 20 is internally threaded and receives an externally threaded plug 22 which may be adjusted to different tensions of spring 36, which will be described later. The right hand end of the member 20 is provided with diametri-

cally opposed slots and is closed by means of a plug or wall member 21, as is clear from Figure 3. Lying within the tubular member 20 and extending through the closure members 21 and 22 with a sliding fit, is a plunger rod 23 provided with a handle grip 24 on the end which projects from the slotted end of the member 20. The end of the rod 23 which extends through the plug 22 is provided with a short lever 25 positioned to engage the roller on the end of a switch lever 26, forming part of the switch 27. The switch 27 is supported from the plate 10 in any suitable manner, as for example by means of the bracket, as shown in Figure 3. The lever 25 holds the switch 27 in one of its two positions when shaft 23 is in the position shown in Figure 3 and forces it to move to its other position when the shaft 23 moves to the position shown in Figure 6.

The right hand end of the rod 23 as shown in Figure 3 is provided with a transversely extending pin 28 which lies in the slots in the end of the member 20 and also lies between the pairs of projections 29 on the outer face of the arm 19 (see also Figure 4). Projecting from the opposite face of the arm 19 is a pair of spaced projections 30 (see also Figure 4) between which lies an ear 31 attached to an externally extending brake 32 engaging the hub of the drum 17. As shown in Figure 4, this brake is loaded by means of a spring 33 which operates to cause the brake band to engage the drum 17 under a pressure which may be readily adjusted by means of the lock nuts which control the tension of the spring 33. The brake structure itself is not novel, it being a simple spring operated externally contracting brake comprising a band surrounding the hub of the drum 17 and lined with a suitable brake lining.

The rod 23 is provided with a notched collar 34 which is pinned thereto, as illustrated in the drawings, and the notch of which is positioned to receive the latch 35 when radially aligned therewith, as illustrated in Figure 5. The latch 35 is mounted upon the arm 16 for movement with it. As clearly shown in Figure 3, a spring 36 lies between the positionable plug 22 and the collar 34, so that shaft 23 is urged to the right under the pressure of spring 36, adjustable by positioning plug 22 as required. Pivoted connected to the arm 16 by the pivot pin 39 is a rod 37 which is slidably mounted in a diametral hole in the guide 38 which is rotatably mounted on the plate 10 as can be seen from Figures 3 and 5. The free end of the rod 37 is threaded and is provided with a pair of lock nuts against which one end of the compression spring 40 rests. The other end of the spring engages the guide 38.

Mounted within the drum 17 in a position to engage an inner face thereof, is a cam 41 which as shown in Figure 7, is pivotally mounted by means of the cap screw 42 upon a standard 44 which in turn is attached to the plate 10. A small compression spring 43 engages the cam 41 tending to move it in a direction opposite the normal direction of rotation of the drum 17, as indicated by the arrow in Figure 4.

A few miscellaneous items remain to be mentioned, as for example the counterweight 19' (see Figure 4) for the lever 18, the carriage 45 which prevents the wire from coming off the idler pulley 18, and the peripheral flanges for the drum 17 (see Figure 3) to form a trough in which the convolutions of the wire on the drum lie.

The operation of this mechanism will now be described. It is to be assumed that the parts are in the position shown in all of the figures, except

Figures 5 and 6. At this time it will be seen that the wire W has been fed from the coil 6 through the guide tube 12, the adjustable drag 13, the eyelet 14, around the idler pulley 15, around the drum 17 a number of times, and around the pulley 18 from which it passes to the wire drawing machine 1. The number of convolutions of wire on the drum 17 will depend upon the time it takes the processing machine, as for example the wire drawing machine 1, to come to a stop after the power supply thereto is shut off. Of course, tied up with this is the consideration of how much wire the processing machine will demand during this stopping period. Sufficient wire should be placed on the drum 17 so that it will not all be used up by the time the processing machine comes to a stop.

During normal conditions of operation the wire will be supplied from the coil 6 to the processing machine. At this time the wire will be supplied to drum 17 at the left hand side (see Figure 4) and be supplied from that drum to and from the pulley 18. The surface of the drum 17 on which the wire convolutions lie is slightly tapered towards the right so that the fresh turns coming in at the left will gradually be borne over towards the right by the succeeding turns, and will be delivered from the layer at the right hand end. The arm 19 is locked against rotation by the pin 28 and the brake 32 merely operates as a drag on the drum 17 to prevent it from overrunning. The engagement of the lug 31 of the brake 32 with the ears 30 on the arm 19 holds the brake stationary while permitting it to prevent overrunning of the drum in an apparent manner. The drag caused by the brake is adjustable as previously explained.

The arm 16 loaded by the spring 40 during the period of normal operation acts as a sort of buffer arm to absorb slight variations in the tension in the wire due to any cause. For example, should the wire feeding from the coil 6 become momentarily locked with adjacent convolutions the increase in tension in the wire may cause the arm 16 to swing downwardly in a counter-clockwise direction towards the dot and dash line position shown in Figure 4. These movements of the arm 16 are buffered by the spring 40 whose effect is adjustable, as previously explained. Should adjacent convolutions of the wire lock with the feeding wire, or should the wire become tangled or kinked in any manner so that the tension in the wire increases sufficiently to cause arm 16 to be pulled down to the dot dash line position of Figure 4, against the resistance of spring 40, then the latch 35 will align with the radial slot in the collar 34. By way of example, if the wire becomes kinked, when that kink reaches the guide tube 12 the supply of wire will stop, causing the arm 16 to immediately swing down to this position. As soon as the latch 35 aligns with the slot and collar 34, spring 36 will force shaft 23 to the position shown in Figure 6. This disengages the pin 28 from the finger 29 on the arm 19 and causes the operation of switch 27 in an obvious manner. At this point it is to be noted that the switch 27 is associated with the power circuit for the motor 2 directly or through control mechanism so that for the normal position of the parts the circuit for the motor is made, in part at least, through the switch 27. However, as soon as switch 27 is moved to the position shown in Figure 6, the supply to the

motor 2 is cut off and the coasting period for the wire drawing machine 1 begins.

The disengagement of the pin 28 from the arm 19 releases that arm so that due to the wire demands of the processing machine, it rotates on the tubular member 28 unwinding the wire from the drum 17 to continue the supply of wire to the wire drawing machine. As viewed from Figure 4, the arm 19 rotates in a clockwise direction, that is in a direction opposite to the normal direction of rotation of the drum 17. During this period the action of the brake 32 is transferred to the arm 19 preventing it from running ahead of the wire requirements of the drawing machine. It is now required that there be a member against which the brake which is now rotating with the arm 19 may react. This is provided by the cam 41 which in the normal operation of drum 17 rotates against its inner surface and is prevented from gripping by the angle of its force against drum 17. The cam 41 lightly engages the inner surface of the drum 17 but is so positioned and shaped that in cooperation with spring 43 it will not interfere with the normal counter-clockwise rotation of drum 17. However, when the action of the brake 32 is transferred to the arm 19 the drum 17 will actually tend to rotate in a clockwise direction with the arm 19, but this is prevented by the cam 41 which swings about pivot pin 42 aided by the spring 43 to grip the drum 17 and lock it against movement. Thus until the wire drawing machine comes to a stop the arm 19 will rotate so as to unwind the wire from the spool on drum 17, with the result that breakage of the wire cannot occur even though the supply from the coil 6 is stopped. As previously mentioned there is sufficient wire on the drum 17 so that the machine 1 is certain to come to a stop before the supply thereof is used up.

Before again starting the wire drawing machine after the trouble is eliminated, as for example the tangle is clear, sufficient turns of wire are replaced on drum 17 by rotating the arm 19 in counter-clockwise direction, Figure 4. This causes the drum 17 to rotate with it through the brake 32 for one revolution, after which arm 19 and drum 17 are mechanically interlocked by the wire itself, so that the supply wire on the drum is replenished. After this the handle 24 is pressed inwardly, that is to the left, Figure 3, moving the rod 23 and the collar 34 to the left until the latch 35 is released, whereupon spring 40 pulls arm 16 up to normal position. By this time the pin 28 has moved between the ears 29 on the arm 19 and the lever 25 has moved back to the position shown in Figure 3. Switch 26 is preferably of a type in which the lever 26 thereof is biased by a spring so that it follows the lever 25 back to the position shown in Figure 3. The machine is again ready for normal operation and the wire drawing machine can be set in motion.

Those skilled in this art will readily appreciate the advantages of a mechanism of this type as residing in the fact that by preventing the breakage of the wire the nuisance of rejoining it at the break and rethreading the processing machine is eliminated. Other advantages are found in the relative simplicity and compactness of the mechanism and the ease with which it may be operated and reset for operation.

From the above description it will be apparent to those skilled in the art that the subject matter of this invention may be embodied in other phys-

ical forms. I do not, therefore, desire to be strictly limited to the disclosure as given for purposes of illustration, but rather to the scope of the claims granted me.

What is claimed is:

1. In a mechanism of the type described, the combination including a support for a strand coil, a normally rotatable carrier positioned to receive and support a plurality of convolutions of said strand, means for guiding the strand thereto, means for guiding the strand therefrom, said last two means being normally stationary as said carrier revolves, so that the number of convolutions on the carrier remains constant, and means for stopping the rotation of said carrier and releasing for rotation the means for guiding the strand therefrom upon the stoppage of the strand supply from the coil to said carrier.
2. In a mechanism of the type described, the combination including a support for a strand coil, a normally rotatable carrier positioned to receive and support a plurality of convolutions of said strand, means for guiding the strand thereto, means for guiding the strand therefrom, said last two means being normally stationary as said carrier revolves, so that the number of convolutions on the carrier remains constant, means for stopping the rotation of said carrier and causing the rotation of the means for guiding the strand therefrom upon the stoppage of the strand supply from the coil to said carrier, and means for locking the carrier against movement during rotation of said means for guiding the strand from the carrier.
3. In the combination of claim 1, means controlled by the means for guiding the strand to said carrier for causing the carrier to stop and the means for guiding the strand from the carrier to rotate.
4. In a machine of the type described, the combination including a support for a strand coil, a rotatable carrier, means pivoted on the axis of the carrier for guiding the strand from the coil to the carrier, means rotatably mounted on the axis of the carrier for delivering the strand from the carrier, means for locking said last means against rotation, and means controlled by the means for guiding the strand to the carrier upon undue increase in tension in the strand for unlocking said delivery means so that it may rotate with respect to said carrier.
5. In a machine of the type described, the combination including a support for a strand coil, a rotatable carrier, means pivoted on the axis of the carrier for guiding the strand from the coil to the carrier, means rotatably mounted on the axis of the carrier for delivering the strand from the carrier, means for locking said last means against rotation, means controlled by the means for guiding the strand to the carrier upon undue increase in tension in the strand for unlocking said delivery means so that it may rotate with respect to said carrier, and a friction device interconnecting the carrier with said delivery means.
6. In a machine of the type described, the combination including a support for a strand coil, a rotatable carrier, means pivoted on the axis of the carrier for guiding the strand from the coil to the carrier, means rotatably mounted on the axis of the carrier for delivering the strand from the carrier, means for locking said last means against rotation, means controlled by the means for guiding the strand to the carrier upon undue increase in tension in the strand for unlocking

said delivery means so that it may rotate with respect to said carrier, a friction device interconnecting the carrier with said delivery means, and means for locking the carrier against rotation with said delivery means.

7. In a mechanism of the type described the combination comprising a support for a strand coil, a rotatable carrier for supporting a desired length of the strand in the form of convolutions, a guiding member pivoted on the axis of the carrier for guiding the strand from the coil to the carrier, a member rotatably mounted on the axis of the carrier for guiding the strand from the carrier, a friction device interconnecting the carrier with said last means, means for locking said delivery means against rotation, and means controlled by said supply guide means for releasing said lock upon movement of said means upon undue increase in tension in the strand.

8. In a mechanism of the type described the combination comprising a support for a strand coil, a rotatable carrier for supporting a desired length of the strand in the form of convolutions, a guiding member pivoted on the axis of the carrier for guiding the strand from the coil to the carrier, a member rotatably mounted on the axis of the carrier for guiding the strand from the carrier, a friction device interconnecting the carrier with said last means, means for locking said delivery means against rotation, means controlled by said supply guide means for releasing said lock upon movement of said means upon undue increase in tension in the strand, and means for holding said carrier against rotation when said delivery means rotates.

9. In a strand supply machine, the combina-

tion including a strand supply support, a normally rotatable drum, a normally stationary rotatably supported means for guiding the strand from said drum and means for causing rotation of the guiding means and stoppage of the drum to supply the strand directly from the drum upon stoppage of the supply of strand to the drum.

10. In the combination of claim 9, said last means being actuated upon the presence of excess pull on the strand going to the drum.

11. In the combination of claim 9, a control device for stopping a machine to which the strand is fed from the strand supply machine, said control device being actuated by said rotation causing means.

12. In a strand supply machine, the combination including a rotatably supported drum, a normally stationary movably supported guide for directing a strand to said drum, rotatably supported means for guiding the strand from the drum, means for holding said second guiding means normally stationary, said last means being released by said first guiding means when the tension in the strand fed thereto unduly increases, whereby said second guiding means is released for rotation, and friction drag means normally acting on said drum but acting on said second guiding means when it rotates.

13. In the combination of claim 12, means for yieldingly resisting movement of said first guiding means, whereby the normal variations in the tension in the strand are absorbed.

14. In the combination of claim 12, means for preventing reverse rotation of said drum while said second guiding means is rotating.

CHARLES M. FORNWALD, JR.
